COMBINED TWIN BED AND SOFA UNIT

Louis Elliott Frey, Los Angeles, Calif.

Application October 24, 1955, Serial No. 38,532

Term of patent 14 years

(Cl. D15—11)

FIG. 1.

FIG. 2.

Fig. 1 is a perspective view showing a combined twin bed and sofa unit embodying my new design in closed position;

Fig. 2 is a perspective view of the same in open position.
I claim:

The ornamental design for a combined twin bed and sofa unit, substantially as shown.
